UNITED STATES PATENT OFFICE.

JOSEPH N. MAHONEY, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,287,722.

Specification of Letters Patent. Patented Dec. 17, 1918.

Application filed July 11, 1916. Serial No. 108,571.

To all whom it may concern:

Be it known that I, JOSEPH N. MAHONEY, a citizen of the United States, and a resident of Wilkinsburg, in the county of Allegheny and State of Pennsylvania, have invented a new and useful Improvement in Electrical Protective Devices, of which the following is a specification.

My invention relates to electrical protective devices and particularly to relay mechanisms that are employed for tripping circuit interrupters upon the occurrence of predetermined conditions.

One object of my invention is to provide a simple and economical relay system of the character indicated that may be operated by current derived from the circuit in connection with which the interrupter is employed, thereby obviating the necessity of employing a separate source of energy for supplying the operating current for its trip coil.

Another object of my invention is to provide a system of the above indicated character that shall have a positive locking means for precluding the operation of the tripping device until the relay has functioned properly.

Copending application Serial No. 850,331, filed July 11, 1914 by B. H. Smith and assigned to the Westinghouse Electric and Manufacturing Company, discloses a relay system that is adapted to supply a trip coil with energy from the circuit in connection with which its interrupter is employed. However, upon the occurrence of relatively high overloads, a device of this type frequently permits the trip coil to operate its movable armature before the relay functions properly. In view of this, I provide a latch for positively locking the trip coil movable armature in its inoperative position until the relay operates.

The single figure of the accompanying drawing is a diagrammatic view of a distributing system embodying my invention.

An electric circuit 1 is provided with an interrupter 2 having a trip coil 3. The trip coil 3 is adapted to be supplied with energy through a transformer 4 and is adapted to be controlled, in its operation, by either an overload or reverse-energy relay 5.

The relay 5 may be delayed or not in its time of operation and comprises a magnetizable core member 6, windings 7 and 8,

an armature 9 and coöperating contact members 10 and 11. An electromagnet 12 comprises a stationary magnetizable core member 13, two windings 14 and 15 and a pivotally-mounted armature 16 that is adapted to be held in engagement with its stationary core member by the force of gravity when the winding 14 is deenergized. The movable armature 18 of the trip coil 3 is provided with a beveled projection 19 that is adapted to engage a similarly beveled projection 20 on the armature 16 for the purpose of so locking the armature 18 as to preclude its operation until the relay 5 has operated to deenergize the electromagnet 12.

One terminal 4^a of the transformer 4 is connected to one terminal of the winding 8 of the relay 5, the other terminal of the winding 8 being connected to one terminal of the winding 14 of the electromagnet 12 and the other terminal of the winding 14 being connected to one terminal of the winding 15 and to the terminal 3^a of the trip coil 3. The other terminal of the winding 15 is connected to the movable contact member 11 of the relay 5, and the terminal 3^b of the trip coil 3 is connected to the terminal 4^b of the transformer 4. The stationary contact member 10 is connected to the terminal 3^a of the trip coil 3.

Under normal conditions, insufficient current traverses the relay 5 to cause its armature to operate. However, sufficient current traverses the winding 14 of the electromagnet to hold the armature 16 in such position as to prevent the trip coil 3 from operating its armature 18. When an overload traverses the circuit 1, sufficient current traverses the winding 8 of the relay 5 to effect engagement of the contact members 10 and 11 and thus close the circuit of the winding 15. The current in the winding 15 will induce a current in the winding 14 in opposition to that which normally traverses it, whereby the core 13 will be substantially demagnetized to permit such movement of the armature 16 upon its pivot as to release the movable armature 18 of the trip coil 3 to trip the circuit interrupter 2.

When the interrupter 2 is tripped, no current traverses the windings 8 and 14 and the trip coil 3, and, consequently, the contact members 10 and 11 will be disengaged, and a spring 21 will move the armature 18 of the trip coil 3 to such position that the force of

gravity will permit the armature 16 to return to its initial position. Thus, when the winding 14 is again energized, the projection 19 of the armature 18 will be in such 5 locked position that it will be permitted to operate only after the relay 5 has functioned. The movement of the armature 16 is so limited by a stationary pin 17 that the projections 19 and 20 are not completely 10 disengaged when the movable armature 18 is actuated. That is, the movement of the projection 19 forces the projection 20 downwardly a sufficient distance, that is limited 15 by the pin 17, to permit it to trip the interrupter 2 without moving completely out of engagement. When the circuit is opened and the spring 21 moves the armature 18 to its initial position, the force of gravity will cause the armature 16 to assume the 20 position shown in the drawing. Thus, when the interrupter is again closed, the device is in such position as to preclude the tripping of the interrupter until the relay operates.

I do not limit my invention to the structures illustrated, as it may be variously modified without departing from the spirit and scope of the invention, as set forth in the appended claims.

I claim as my invention:

30 1. In an electric circuit, the combination with a circuit interrupter and a trip coil therefor, of a relay operatively connected to the circuit, and electro-magnetic means connected in circuit with the relay for locking the trip coil armature in its inoperative position until the relay operates.

2. In an electric circuit, the combination with a circuit interrupter and a trip coil therefor, of a relay operatively connected 40 to the circuit and in series with the trip coil, and electro-magnetic means connected in circuit with the relay for locking the trip coil armature in its inoperative position until the relay operates.

45 3. In an electric circuit, the combination with a circuit interrupter and a trip coil therefor, of a relay operatively connected to the circuit and in series with the trip coil, and means connected in series with the relay and adapted to be controlled by the relay for locking the trip coil armature in its inoperative position under predetermined conditions.

50 4. In an electric circuit, the combination with a circuit interrupter and a trip coil therefor, of a relay adapted to be supplied with current from the circuit in accordance with the current traversing the circuit, and

means connected in series with the relay and the trip coil for locking the trip coil armature in its inoperative position under predetermined conditions. 60

5. In an electric circuit, the combination with a circuit interrupter and a trip coil therefor, of a relay adapted to be supplied with current from the circuit in accordance with the current traversing the circuit, and means connected in series with the relay and the trip coil for locking the trip coil armature in its inoperative position until the relay operates. 65

6. In an electric circuit, the combination with a circuit interrupter and a trip coil therefor, of a relay adapted to be supplied with current from the circuit in accordance with the current traversing the circuit, and electro-responsive means connected in series with the relay and the trip coil and adapted to be controlled by the relay for holding the trip coil armature in a predetermined position until the relay operates, irrespective of the current traversing the same. 75

7. In an electric circuit, the combination with a circuit interrupter and a trip coil therefor, of a relay responsive to predetermined conditions in the circuit, a latch for the trip coil armature, and an electromagnet connected in series with the relay and the trip coil for normally holding the latch in such position as to prevent the operation 80 of the trip coil armature until the relay operates. 85

8. In an electric circuit, the combination with a circuit interrupter, a trip coil therefor, and a series transformer operatively connected to the circuit, of a relay, a latch for the trip coil armature, and an electromagnet for controlling the latch having a winding that is connected in series with the transformer, the relay and the trip coil, and a neutralizing winding that is adapted to be controlled by the relay. 90 95

9. In an electric circuit, the combination with a circuit interrupter and a trip coil therefor, of a transformer operatively connected to the circuit, a relay connected in series with the transformer and the trip coil, and means controlled by the relay for locking the trip-coil armature in its inoperative position under predetermined conditions. 100 105

In testimony whereof, I have hereunto subscribed my name this 29th day of June 1916.

JOSEPH N. MAHONEY.
